(57) **CLAIM**

The ornamental design for a racking system, as shown and described.

DESCRIPTION

FIG. 1 is a front perspective view of a racking system showing my new design;

FIG. 2 is a rear perspective view thereof;

FIG. 3 is a front elevation view thereof;

FIG. 4 is a rear elevation view thereof;

FIG. 5 is a second rear perspective view thereof;

FIG. 6 is a right side elevation view thereof;

FIG. 7 is a left side elevation view thereof;

FIG. 8 is a top perspective view thereof;

FIG. 9 is a bottom perspective view thereof;

FIG. 10 is a second front elevation view thereof; and,

FIG. 11 is a second rear elevation view thereof.

The broken lines shown represent unclaimed subject matter and form no part of the claimed design.
